CONTROL APPARATUS AND BRACKET
THEREFORHenry A. Rowe, Cambridge, Mass., assignor to
Massachusetts Institute of Technology, Cam-
bridge, Mass.

Application June 22, 1945, Serial No. 600,871

4 Claims. (Cl. 89—37)

1

This invention relates to apparatus for controlling movements of a gun mount, and a collapsible bracket therefor. For effective use of anti-aircraft guns, it is necessary that the guns be capable of rapid movement both in azimuth and elevation, and that such movements be accurately controlled. For this purpose, sensitive servo-mechanisms are employed, these mechanisms being in many cases controlled by apparatus contained in a case or cabinet having a pair of hand grips by which the mechanism within the cabinet can be manually operated. In order to facilitate the manipulation of such grips by the gunner, the cabinet by which the grips are carried is supported over the lap of the seated gunner so that the grips are within easy and convenient reach. According to the present invention, a collapsible bracket is attached to the cabinet to support it in the proper position when it is in use, and to support it in a raised position when not in use, so that the gunner can more easily climb into or out of his seat, and so that auxiliary control apparatus for moving the gun mount can be employed, the position of the auxiliary control apparatus being such that access to it is obstructed by the control cabinet when the latter is in position for use.

The invention is more fully hereinafter described, and an embodiment is illustrated in the drawing of which:

Figure 1 is a side elevation of a gun mount showing a control cabinet and supporting means therefor.

Figure 2 is a similar view, showing the cabinet and support in a different position, and

Figure 3 is a rear elevation of the cabinet and its support.

The drawing shows the invention as used with an anti-aircraft gun 10 and its mount which are rotatable on a pedestal 12. Guns of this type are usually supplied with power mechanisms by which they can be easily and accurately trained and pointed. Control mechanism, the details of which are not pertinent to this invention, is contained in a cabinet 14. On the cabinet are mounted a pair of grips 16 and 18 manipulation of which causes the power mechanism to impart desired movements to the mount. A seat 20 with a backrest 22 is adjustably mounted on a bracket 24 supported by the gun mount. Footrests 26 and 28 are also carried by the gun mount in a suitable position forward of the seat 20. For effective operation of the gun control means, the cabinet should be in such a position, when in use, that the grips 16 and 18 are within easy

2

reach of the gunner who is seated on the seat 20. Such position is preferably over the outstretched legs of the gunner and is illustrated in Figure 1. When the cabinet is in this position, the clearance between its rear end and the seat is such that the gunner could get into and out of the seat only with great difficulty. The cabinet is therefore mounted in such a way that it can be swung up to a raised position in which it is out of the gunner's way. In its raised position the cabinet is also clear of a hand-crank 30 which is detachably mounted at the adjacent side of the gun mount and is conveniently located with reference to the gunner when it is in position for use as shown in Figure 2. This crank is for manual operation of the gun if power is not available. Since both the crank 30 and the grips 16 and 18 must be within easy reach when wanted, the cabinet when in the position shown in Figure 1 interferes with the use of the crank. Hence, when the gunner desires to use the crank 30, he first swings the cabinet up to its raised position.

For this purpose the cabinet 14 is hinged at or near its forward end to a suitable fixed bracket 32 having a rod or hinge pin 34 rigidly secured thereto on which are rockably mounted a pair of bearing members 36 attached to the cabinet. The bracket 32 including the rod 34 having a fixed arm 48 thereon may be secured to any convenient part of the gun mount or framework carried thereby. The rear end of the cabinet is supported by a leg or stanchion 38 which is pivotally attached at its upper end between a pair of ears 40 attached to the cabinet. When the cabinet is in its position for use, the lower end of the leg 38 is secured between a pair of ears 42 mounted on some part of the gun mount, a pin 44 being thrust through aligned holes in the ears 42 and the lower end of the leg to secure the joint.

When the gunner is ready to leave his seat, he reaches down and removes the pin 44, thus releasing the lower end of the leg 38. The cabinet 45 can now be swung up to its raised position in which position it can be secured by thrusting the pin 44 through the hole in the lower end of the leg 38 after that hole has been brought into alignment with a hole 46 in an arm 48 which is fixed adjustably on the rod 34 by any suitable adjustable fixing means on arm 48 at rod 34 as indicated in Figure 3, arm 48 projecting downwardly from rod 34 in normal fixed position. In order to guide the lower end of the rod 38 so that the hole therein will move into alignment with

the hole 46, a link 50 is pivoted at 52 to the arm 48 at a point below the hole 46 and at 54 to an intermediate point of the leg 38. This link also serves to limit the extent of the upward swing of the cabinet 14. Thus the gunner need only swing the cabinet up as far as it will go, then push the leg 38 forward slightly to bring the holes in the leg 38 and arm 48 into alignment to receive the pin 44. This position is illustrated in Figure 2. After the gunner has resumed his seat, the pin 44 is pulled out to release the cabinet which can then be swung down to its horizontal position. The link 50 controls the swing of the leg 38 so that the lower end of the latter moves into alignment with the ears 42 when the cabinet reaches its horizontal position.

I claim:

1. In combination with a gun mount, a seat for the gunner, a control cabinet, and means for supporting said cabinet comprising a hinge device between the mount and the forward end portion of the cabinet, a leg pivotally connected to said cabinet near the rear end thereof and releasably secured at its lower end to the mount, a fixed bracket adjacent to said hinge device, a link extending from said bracket to an intermediate point of said leg, and means for securing the lower end of the leg alternatively to the gun mount when the cabinet is in a horizontal position over the lap of a seated gunner or to said bracket when the cabinet is swung back to a raised position.

2. In combination with a gun mount, a seat for the gunner, a control cabinet, and means for supporting the cabinet alternatively in a substantially horizontal position for use or in a raised position to permit the gunner to enter or leave his seat, said supporting means comprising a hinge device connecting the cabinet near its forward end to the mount, a leg having its upper end pivotally attached to the cabinet near the rear end thereof and its lower end detachably

secured to the mount when the cabinet is in its horizontal position, fixed means to which the lower end of the leg can be detachably secured when the cabinet is in its raised position, and means for limiting the upward swing of the cabinet.

3. In combination with a gun mount, a seat for the gunner, a control cabinet, and means for supporting the cabinet alternatively in a substantially horizontal position for use or in a raised position to permit the gunner to enter or leave his seat, said supporting means comprising a horizontal rod rigidly secured to said mount, pivot means rockably connecting said cabinet near its forward end with said rod, a bracket arm adjustably mounted on said rod and extending radially therefrom, a leg pivotally attached to said cabinet near the rear end thereof and extending vertically downward therefrom when the cabinet is in its horizontal position, a link pivotally attached at one end to said leg at an intermediate point thereof and at the other end to said bracket arm, and means for detachably securing the free end of said leg to the mount when the cabinet is in its horizontal position or to said bracket arm when the cabinet is in its raised position.

4. In combination with a gun mount, a seat for the gunner, a control cabinet, and means for supporting the cabinet alternatively in a substantially horizontal position for use or in a raised position when not in use, said supporting means comprising a hinged device connecting said cabinet to said mount, and a leg pivotally attached at one end to said cabinet and adapted to be detachably secured at the other end to said mount when said cabinet is in a substantially horizontal position and alternatively to fixed means on said mount when said cabinet is in a raised position.

HENRY A. ROWE.
